MATTRESS CONSTRUCTION

Max Weisberg, Brooklyn, N. Y.

Application October 26, 1942, Serial No. 463,362

3 Claims. (Cl. 5—359)

The present invention relates to improvements in mattress construction, and has for its primary object, the provision of novel, yet simple and highly effective means, whereby the usual tendency for the filling material to become compacted at certain spots, with consequent lumping at others, caused by the unequal disposition of the body weight on the mattress, and the normal bulges of the human torso, is substantially nullified.

The present invention is based upon the discovery by me that where the filling material is given oblique support at relatively closely spaced points within the mattress, such support tends to resist compaction of the filling material, at least in part, by transmitting the force of the body pressure to other parts of the mattress, and in part by deflecting said force back at an angle more or less acute to the direction of the incident force or pressure.

In carrying out my invention, I provide the interior of the mattress with a series of inclined webs, which preferably extend transversely across the width thereof and are stitched each to the top and bottom fabric of the mattress. Thereafter suitable filling material is inserted in the pockets or compartments circumscribed or bounded by said webs, sides and top and bottom fabric of the mattress.

The accompanying sheet of drawings illustrates my invention.

Fig. 1 is a perspective view of one embodiment of my invention, portions being broken away to show the internal construction in section.

Fig. 2 is a fragmentary perspective view of a modification of the embodiment illustrated in Fig. 1.

Fig. 3 is a fragmentary section of a further modification.

Throughout the drawing, like reference characters indicate like parts.

Referring more particularly to Fig. 1, it will be seen that the mattress 1 is divided into substantially prism or wedge-shaped compartments 2, by the interposition of a pleat-like fabric sheet 3, the creased edges of which are stitched as shown at 4, to the top and bottom layers 1a, 1b, of the covering fabric of the mattress, in such manner as to provide inclined webs 5 for affording oblique support for the filling material 6 disposed within the several prism or wedge-shaped compartments 2.

In order further to strengthen the mattress against sagging and to provide resistance against compaction and compressive pressures, there is provided in each triangular cell 2, a horizontal semi-rigid, yet flexible separator 11, as for instance, a sheet of corrugated board, extending from web to web, and running the full width of the mattress, thus further dividing the com-

partments or cells. These separators are placed substantially midway between the top and bottom of the mattress and the filling material placed within the cells. In Fig. 2, instead of using the 5 corrugated board separator, the additional resistance to compaction and compressive pressure is provided by horizontal webs 7, separating each wedge-shaped compartment into wedge-shape 8 and trapezoidal compartments 9, said webs 7, 10 being preferably stitched as at 10, to adjacent inclined webs 5, at points more or less midway thereof. It will be observed that this arrangement provides two tiers of compartments, an upper tier and a lower tier. The upper tier consists of a series of substantially trapezoidal compartments 9, intercepted by triangular compartments 8, while the lower tier has a similar arrangement but in reverse order. I have found 15 this latter construction particularly efficient, especially where the horizontal webs 5, are in somewhat the staggered relation, shown in Fig. 2, for here, it seems, the effect of the intervening wedges of filling material on the adjacent trapezoidal compartments is to more positively oppose compaction of the filling material in said 20 latter compartments by seemingly interposing a force in the opposite direction, in addition to the action first ascribed by virtue of the oblique support.

30 Having thus described my invention, what I claim is:

1. A mattress having transversely extending partitions dividing the interior of the mattress into a series of wedge-shaped compartments and 35 having horizontal partitions of flexible semi-rigid material sub-dividing the entire length of each wedge-shaped compartment, said horizontal partitions being arranged in staggered relation with respect to the horizontal partitions in the next adjacent compartments.

2. A mattress having transversely extending partitions dividing the interior of the mattress into a series of wedge-shaped compartments and having horizontal partitions of corrugated board 45 sub-dividing the entire length of each wedge-shaped compartment, said horizontal partitions being arranged in staggered relation with respect to the horizontal partitions in the next adjacent compartments.

50 3. A mattress having transversely extending partitions dividing the interior of the mattress into a series of wedge-shaped compartments and having horizontal partitions sub-dividing each wedge-shaped compartment, said horizontal partitions being arranged in staggered parallel relation with respect to the horizontal partitions in the next adjacent compartments, and the length 55 of the partitions and the compartments being substantially coextensive.

MAX WEISBERG.
